NATURAL GAS PRODUCTION

George Judson Baldwin and George Wesley Addy,
Cayuga, Ontario, Canada

Application May 16, 1938, Serial No. 208,327

5 Claims. (Cl. 103—234)

This invention relates to improvements in the method of ejecting seepage water from natural gas wells and an automatic apparatus therefor.

Natural gas wells, notwithstanding all known precautions such as well casings, are usually encroached by a considerable quantity of water which gradually seeps in from the water bearing sand which is mostly encountered above the gas sand, until it rises to the point where it interferes with the flow of gas to the surface, whereupon the gas flow must be closed off and the water siphoned to the surface through a pipe provided for the purpose, by means of the gas pressure then transferred wholly to the water surface.

15 In many instances the volume of water becomes too great for the normal pressure of the gas to eject it to the surface and in consequence either the well is abandoned or the water must be pumped to the surface at great expense and considerable loss of time. In fact on many occasions it is more economical to abandon the well than to attempt water evacuation.

25 The principal object of this invention is to provide an improved apparatus and process for removing collected water from the bottom of a gas well, the apparatus and process being such that the pressure of the gas in the well forms the sole means for expelling collected water.

A second important object is to provide an apparatus of the class specified which will be simple, durable, efficient, and inexpensive to produce and to install.

With the above and other objects in view as will be hereinafter apparent, the invention consists in general of certain novel details of construction and combinations of parts hereinafter fully described, illustrated in the accompanying drawing and specifically claimed.

Figure 1 is a diagrammatic section of a characteristic gas well showing a typical position therein of the invention when used; and,

Figure 2 is an elevation in median section of the apparatus constructed in accordance with this invention.

45 In the figure showing a gas well, A indicates the well shaft; B, the gas tubing; C, the water pipe; D, the rubber packer; E, the water intake port; F, the ground surface; G, the usual top soil; H, rock; J, slate; K, water sand; L, second strata 50 of slate; and M, the gas sand. Introduced in the water pipe is the apparatus constituting the subject matter of this invention and which is indicated in general by N in Figure 1 and shown separately in sectional detail in Figure 2.

55 First it should be understood that in evacuat-

ing water from a gas well the pressure of gas on the surface of the water in the well tends to force the water up the pipe C. If the pressure is not sufficient to force the water to the surface of the well when pipe C is valveularly opened at the well head, the water will surge beyond the level where the weight of column of water in pipe C and pressure forcing water up pipe C are equal and thereafter the water in pipe C will recede and equalize unless such recession is checked.

10 In its present embodiment the invention consists of a tubular device indicated in general by N and situated in the water pipe C above the level of the water sand. It has walls N' of internally increased thickness close to its ends which are 15 internally pipe threaded at N² for the reception of the conforming externally threaded ends of the contiguous pipe sections between which it is interposed for use.

Slidably arranged in the cylindrical lowermost 20 end of the tube N is a hollow piston or plunger having an upwardly extending skirt 10. In the piston head 10' is an automatic valve, preferably of the ball type, the ball being indicated by 11 and its seat in the piston head by 12. It will be 25 seen that this valve will act to permit upward flow and to prevent down or return flow. It will be observed also that upon movement of the piston to bottom dead center its frustro-conical or truncated head will seat upon the shoulder 13 30 formed by the reduced internal diameter of the tube and when thus seated will valveularly close the tube against leakage between the piston and cylinder wall.

35 Journalled in the skirt of the piston is a wrist pin 14 upwardly from which extends a rod 15. Well above the piston this rod passes through a sleeve 16 which depends coaxially of the tube from a bracket 17 extending inwardly from the tube wall. The bracket has a passage 18 leading 40 from outside the tube to inside said sleeve.

The upper end of the rod 15 terminates in a head 19 the diameter of which conforms to the internal diameter of the sleeve, and when the piston and rod are at upper dead center the head 45 19 closes the passage 18. The head 19 is provided with a conical tip 20 adapted to seat against the shoulder 21 formed at the mouth of the sleeve by reducing the internal diameter thereof, thereby constituting a needle valve to close the core of 50 50 the sleeve from the tube.

The lower end of the sleeve is permanently closed by means of a plug 22 which is cored in conformity to the rod 15 and also serves as a guide therefor. Sealing the sleeve is a packing 55

ring 23 surmounted by a packing retaining washer 24 which further serves as seat for a helical spring 25 which expands against the shoulder of the rod head 19 for normal closure retainance of that valve.

5 In operation, the valve B' is closed thus building up gas pressure in the well. The water pipe C, in which the tube N is inserted, is then opened by opening valve C', thus releasing pressure at 10 the head of pipe C. The water in well bottom is then forced up the pipe C and through the tube N, with such velocity that the water will surge above the normal level that the gas pressure will hold, whereupon the returning surge of water 15 in pipe C automatically closes ball valve and divides the column of water. Coincident with closure of the ball valve the weight of the upper part of the column of water falls upon the piston, forcing piston to the lower end of its movement, 20 thereby opening needle valve for the admission of gas into water pipe C, under the upper column of water, whereupon the upper column of water is then forced up the pipe C and ejected at the well head. Upon the reduction of the weight 25 of the upper column on the piston the needle valve assisted by the spring will close and shut off the gas at this point, allowing water in well bottom to be forced through tube N, up portion of pipe C previously evacuated. Thus the cycle 30 is repeated again and again until evacuation is complete.

There has thus been provided a simple and efficient device of the kind described and for the purpose specified.

35 It is obvious that minor changes may be made in the form and construction of the invention without departing from the material spirit thereof. It is not, therefore, desired to confine the invention to the exact form herein shown and described, but it is desired to include all such as 40 properly come within the scope claimed.

We claim:

1. A tubular body for insertion in a pipe line, an 45 internal valve seat in said body, a piston including a skirt and a frusto-conical piston head having an axial opening, said head being adapted for engagement with said seat, a ball movably confined within the skirt and adapted for engagement with the rim of said opening, a piston rod 50 associated with the piston, means in the opposite end of the tubular body establishing communication through the body wall, and a shut-off valve carried by the piston rod and associated with said means and controlled by the movement of the piston to close said means when 55 the piston is in one position and to open said means when the piston is in another position.

2. In a device of the kind described, a casing arranged for vertically positioning in a well, a tubular piston slidably mounted in the lower part 60 of said casing, and upwardly opening check valve at the lower end of said piston, a gas inlet at the upper part of the casing affording communication from the exterior to the interior of the casing, a valve normally closing said gas inlet and movable downwardly in the casing to open the

inlet, a tubular guide extending downwardly in said casing, a valve stem carrying said valve and having its lower end projecting downwardly from the guide and connected to said piston, and a spring in said tubular guide urging said valve to closed position.

3. In a device of the kind described, a casing arranged for interposition in the water flow line of a gas well, a tubular piston slidably mounted in the lower part of said casing and having an 10 upwardly facing valve seat at its lower end, a ball valve normally resting on said seat, a gas inlet at the upper part of the casing affording communication from the exterior to the interior of the casing, a valve normally closing said gas 15 inlet and movable downwardly in the casing to open the inlet, a tubular guide extending downwardly in said casing, a valve stem carrying said valve and having its lower end projecting downwardly from the guide, a cross member extending 20 across the upper part of said piston and supported in the piston wall, means connecting said valve stem and cross member, and a spring in said tubular guide urging said valve to closed position. 25

4. In a device of the kind described, a casing arranged for interposition in the water flow line of a gas well, a tubular piston mounted in the lower part of said casing, an upwardly opening check valve at the lower end of said piston, a gas inlet at the upper part of the casing affording communication from the exterior to the interior of the casing, a valve normally closing said gas inlet and movable downwardly to open the inlet, a tubular guide extending downwardly 35 in said casing and having an open lower end, a tubular closure fitted in the lower end of said guide, a valve stem carrying said valve and slidably fitting said closure, means connecting the lower end of the valve stem to the piston, and 40 a spring in said tubular guide between said closure and the last mentioned valve.

5. In a device of the kind described, a casing arranged for connection in the water flow line of a gas well, a tubular piston slidably mounted 45 in the lower part of said casing and having an inverted frusto-conical bottom providing a centrally disposed opening, said bottom forming a valve seat, a ball valve normally seating on said bottom, a gas inlet at the upper part of the casing affording communication from the exterior to the interior of the casing, said gas inlet having a horizontal leg extending radially in the casing and a vertical leg opening upwardly from the inner end of the horizontal leg, a tubular guide 50 extending downwardly from the lower side of said horizontal leg in alignment with the vertical leg, a gas valve located at the junction of the horizontal and vertical legs of the inlet and normally closing said inlet, said valve being slidable downwardly in said guide, a valve stem connecting said piston and said gas valve, and a spring urging said gas valve to closed position. 55
